UNITED STATES PATENT OFFICE.

OLIN H. BAGLEY, OF KNAPPA, OREGON.

GOLD-SAVING APPARATUS.

SPECIFICATION forming part of Letters Patent No. 394,636, dated December 18, 1888.

Application filed March 15, 1888. Serial No. 267,281. (No model.)

To all whom it may concern:

Be it known that I, OLIN H. BAGLEY, of Knappa, in the county of Clatsop and State of Oregon, have invented an Improvement in 5 Gold-Saving Apparatus; and I hereby declare the following to be a full, clear, and exact description of the same.

My invention relates to the class of machines or apparatus for separating the gold 10 from the ore-pulp or from auriferous sand, earth, or gravel; and my invention consists in the constructions and combinations of devices which I shall hereinafter fully describe and claim.

15 The object of my invention is to provide a simple and effective machine for saving gold.

Referring to the accompanying drawings for a more complete explanation of my invention, Figure 1 is a perspective view of my 20 apparatus, the screen G and directing-plate H being broken to show the table D. Fig. 2 is a longitudinal vertical section. Fig. 3 is a vertical cross-section. Fig. 4 is a view showing the manner in which the sections of table 25 D are united. Fig. 5 is a perspective view showing the make-up of a single section with a form of table surface. Fig. 6 shows a modified form of surface.

A is the bed-frame of the machine, having 30 at its corners standards a, from the tops of which is suspended, by means of hangers b, the shaking-frame B. Standards b' rise from the sides of the shaking-frame and supports cross-bars b², through which pass eyes or 35 staples b³, receiving nuts b⁴, by which they may be adjusted. From these staples depend hangers c, which suspend the frame-work C of the separating-table D. This table consists of a plate or plates having any suitable separating or concentrating surface, of which a 40 fuller description will presently be given. The table D is perforated at d and communicates underneath with the flanges E, by which the material may be properly directed into a 45 chute or box below.

The frame C of the separating-table D has a width enough less than the width of the shaking-frame B, in which it hangs, to enable it to have a movement of its own within said 50 frame, this movement being limited and converted into a jarring motion by means of bumpers c', attached to its sides and adapted

to come in contact with the sides of the shaking-frame B.

Mounted in bearings f on the sills of the 55 main frame A at one side is a power-shaft, F, having on one end the pulley f', by which rotation is imparted, and having also the cranks f², from which connecting-rods f³ extend to a rod or bar, b⁵, attached to the shaking-frame B. 60

By rotating the crank-shaft F the shaking-frame B has imparted to it a reciprocating motion about its hanger-connections as centers, and the table-frame C, being suspended from the shaking-frame B, receives a similar 65 motion, this, however, being changed by the jar which it receives from the contact of its bumpers with the sides of the shaking-frame, so that the table, therefore, has a peculiar 70 side shake and jar, which is found very effective in concentrating the precious particles upon the surface of the table.

The table D, although it may be, as before stated, of any suitable construction for the purpose of separating the material, is preferably made with elevated and depressed portions, the perforations d being made in the elevated portions, so that the lighter and worthless materials lying at the top of the 75 mass may pass off through the perforations, 80 while the heavier and precious material is concentrated and confined within the depressions of the table.

Now, in order to properly feed the material to the table, I have near the upper portion of 85 the table-frame C a screen-plate, G, which is set at a slight incline. The material is fed upon this plate, and the larger gravel, rocks, sticks, &c., failing to pass through the screen move off by gravity down the incline, while 90 the auriferous earth, sand, pulp, and smaller materials pass through the screen.

In order to direct it properly upon the table, I have between the screen-plate G and the surface of the table a directing-plate, H, 95 which is provided with perforations h, located directly over the depressions of the separating-table, so that the material is fed first into the depressions, thus avoiding the loss which would occur if it were fed directly over the 100 perforations d in the table. By interposing the plate H between the screen-plate G and the table I am enabled to make a far less number of holes in said plate, because the

plate H does not act as a screen, but simply as a means for directing the promiscuously-falling mass into the depressions of the concentrating-surface, thus avoiding perforations in the elevated portions of said surface.

The table D may have only a single layer or a double one, such as shown, one plate being directly over the other, the perforations in one occupying an intervening plane to those in the other, so that the material fed upon the upper plate falls into the depressions of the lower plate and not directly into its perforations. From the lower plate the worthless material passes through the perforations and is guided by the directing-plates E below into a chute or box.

The elevated and depressed portions of the table may be formed by corrugations, ruffles of any character, or by having a rim flange or burr around each perforation, as shown by d' in Figs. 4 and 5, and these may be used with a surface otherwise either smooth or corrugated. The flanges or burrs present only another form of the broken or uneven surface, which permits the settling of the heavier materials and the passing off of the lighter ones; or the perforations, instead of being round, may be slits, as shown at d² in Fig. 6, said slits being surrounded by the elevated flanges d', as before.

The separating-table may be all in one piece; but I prefer to make it in sections of the following novel construction: By referring to Fig. 5 it will be seen that a short section of plate is provided with side flanges, I, having grooves on their inner surfaces, in which the edges of the plate-section are fitted, pieces of rubber J being placed in the grooves for forming a tight joint, which joint is completed and the side flanges held to place by means of a bolt or bolts, K, passing under the plates and through the side flanges and receiving the nuts k, by which the whole is tightened up. The end of one section of plate is formed with a flange, L, which fits into an oppositely-bent flange, l, on the adjacent section of plate, as shown in Fig. 4, whereby the two sections may be readily put together, leaving the general surface continuous. By this construction of the separating-table in sections I can readily fit them to their places in the machine and remove them again, so that I can substitute one form of plate for another with facility. A further advantage is that the plates, when they have to be cleaned, by removing the concentrations which are left in the depressions, may be readily handled by removing the bolts K, taking off the side flanges, I, and by means of a proper rubber, brush, or scraper have their depressed portions cleaned of the concentrates.

I am aware that in concentrating-machines there are separating-surfaces which are corrugated, rifled, or otherwise broken or uneven, and I do not therefore claim herein such a surface, broadly.

Having thus described my invention, what I claim as new, and desire to secure by Letters Patent, is—

1. In a gold-saving apparatus, a fixed bed-frame having standards, a frame having standards, and freely-swinging standards suspending it from the standard of the bed-frame, in combination with a frame loosely fitting within the suspended frame and having bumpers on its sides, a separating-table carried by the inner frame, freely-playing hangers suspending it from the standards of the outer frame, a crank-shaft on the bed-frame, and connecting-links to the outer frame, whereby it receives a swinging motion and imparts an independent swinging jarring motion to the inner frame and separating-table, substantially as herein described.

2. In a gold-saving apparatus, a separating-table having depressed and elevated portions with perforations in the elevated portions, in combination with a screen-plate above and an intervening directing-plate provided with perforations located over the depressed portions of the separating-table, substantially as herein described.

3. In a gold-saving apparatus, a fixed bed-frame and a swinging or shaking frame suspended therefrom, in combination with a separating-table having a frame suspended from and within the shaking-frame, whereby it receives a shaking jarring motion, as described, said table having elevated and depressed portions with perforations in the elevated portions, a screen-plate carried by the table-frame and lying over its separating-table, and an intervening directing-plate carried by said frame and provided with perforations over the depressed portions of the separating-table, substantially as herein described.

4. In a gold-saving apparatus, a separating-table having elevated and depressed portions with perforations in the elevated portions, and a second table having similar elevated and depressed portions with perforations in the elevated portions, said second table being located under the first and so arranged that the perforations of the upper table shall be over the depressed portions of the lower table, substantially as herein described.

In witness whereof I have hereunto set my hand.

OLIN H. BAGLEY.
